UNITED STATES PATENT OFFICE.

THOMAS MORRELL MOORE, OF SAN FRANCISCO, CALIFORNIA, ASSIGNOR TO HENRY P. BROWNING, OF MONTCLAIR, NEW JERSEY.

DESIGN FOR AN ARTICLE OF MANUFACTURE.

45,765.

Specification for Design.

Patented May 12, 1914.

Application filed May 25, 1912. Serial No. 699,807. Term of patent 14 years.

To all whom it may concern:

Be it known that I, THOMAS MORRELL MOORE, a citizen of the United States, and residing at San Francisco, in the county of San Francisco, State of California, have invented a new, original, and ornamental Design for an Article of Manufacture, of which the following is a specification, reference being had to the accompanying drawing, forming a part hereof.

The figure shows an ornamental design which is adapted to be placed on any

article of manufacture for ornamental purposes.

I claim:

The ornamental design for an article of manufacture, as shown and described.

Signed at the borough of Manhattan, in the city, county and State of New York, this 24th day of May, 1912.

THOMAS MORRELL MOORE.
